[57] CLAIM

The ornamental design for a bottle, as shown and described.

DESCRIPTION

FIG. 1 is a front and rear elevational view of the bottle incorporating our new design;

FIG. 2 is a right and left side elevational view thereof;

FIG. 3 is a top plan view thereof;

FIG. 4 is a bottom plan view thereof; and,

FIG. 5 is a perspective view thereof.

The broken line showing of a bottle cap is for illustrative purposes only and does not form part of the claimed design.

FIG. 1

FIG. 2

FIG. 3

FIG. 4

FIG. 5
